UNITED STATES PATENT OFFICE.

JAMES WYVELL, OF BRECKENRIDGE, MINNESOTA.

ORGAN.

SPECIFICATION forming part of Letters Patent No. 655,594, dated August 7, 1900.

Application filed August 27, 1898. Serial No. 689,628. (No model.)

To all whom it may concern:

Be it known that I, JAMES WYVELL, a citizen of the United States, residing at Breckenridge, in the county of Wilkin and State of Minnesota, have invented certain new and useful Improvements in Organs; and I do hereby declare the following to be a full, clear, and exact description of the invention, such as will enable others skilled in the art to which it applies to make and use the same.

My invention relates to organs, and particularly to reed-organs; and it has for its object to improve the same in the several points hereinafter specifically set forth, whereby improved actions are obtained and whereby the construction is simplified and reduced in cost.

The invention consists of the novel devices and combinations of devices hereinafter described, and defined in the claims.

The preferred form of my invention as applied to a reed-organ is illustrated in the accompanying drawings, wherein like characters indicate like parts throughout the several views.

Figure 1 is a perspective view of parts of a reed-organ having my improvements applied thereto, the said view being taken from the front of the organ and the case and many other parts of the organ being removed. Fig.

2 is a detail in right side elevation of certain of the parts shown in Fig. 1. Fig. 3 is a perspective view of the parts shown in Fig. 1 looking at the rear of the same. Fig. 4 is a plan view of the stop-frame and the stops, certain parts being broken away. Fig. 5 is a perspective view of a portion of the parts shown in Fig. 4, the same being shown as sectioned on the line $x^5 x^5$ of said Fig. 4 and some parts being broken away. Fig. 6 is a

transverse section taken on the line $x^6 x^6$ of Fig. 4. Fig. 7 is a detail view in perspective, showing one of the detachable connections employed in the device. Fig. 8 is a plan view of one part of the connection shown in Fig. 7, and Fig. 9 is a detail view in perspective of an end section of one of the flexible stop-cords.

In the drawings the keyboard of the organ is shown as exceedingly limited in range; but this will suffice as well for the purposes of this case as would the illustration of a complete keyboard.

In the illustration given, 1 indicates a base portion on which the parallel end plates 2 are vertically supported. The rectangular stop-frame 3 extends transversely across the end plates 2 and is rigidly secured to the upper rear portions of the same.

4 indicates the keys of the keyboard, which keys are mounted and operate in the ordinary manner.

5 and 6 indicate the swell-shutters, which in this arrangement may be designated, respectively, as the "first" and "second" swell-shutters. As is usual, these swell-shutters 65 are hinged, as shown at 7 and 8, respectively.

9, 10, 11, and 12 indicate the mute-valves, which are hinged at 13. More specifically stated, the valves 9 and 10 are respectively the front treble and bass mute-valves, and 70 the valves 11 and 12 are likewise the rear treble and bass mute-valves. The ends of these valves project through suitable passages in the end plates 2 and are operated upon by actuating connections constructed 75 in accordance with my invention and to be hereinafter described.

14 and 15 indicate, respectively, the operating-leaves of the treble and bass octave couplers, the same, as shown, being hinged 80 at 16.

The parts so far described in detail are the ordinary reed-organ construction, the functions of which are well understood, and hence for the purposes of this case need not be further illustrated.

In the ordinary organ construction the stops when moved into operative positions are extended outward over the keys, so that in striking certain chords they are very liable 90 to be struck by the fingers and accidentally thrown back into inoperative position. In my improved construction, wherein the stops are mounted for rotary motion, it is not necessary to pull the same out over the keys when they 95 are rendered operative, and hence the difficulty above noted is obviated. a indicates a series of these stops, as shown, eight in number, which are mounted for rotary but fixed against endwise movements in the stop-frame 100 3. All of these stops except the extreme left-hand member, with respect to Fig. 1, are provided with removable end disks or caps a' , having crank or eccentric pins a^2 , and said

left-hand member is provided with a plane disk or cap a^3 . The stops a are limited in their movements toward their normal positions, as shown, by means of pins a^4 and a^5 , 5 respectively, on said stops a and the stop-frame 3, and it will be noted that the four right-hand and the four left-hand stops are adapted to be turned in opposite directions. The connections between these stops and the 10 mutes or other devices which they control will be described after having described the knee-swell devices.

For the purposes of this case the device 15 which simultaneously operates the treble and bass mute-valves and the treble and bass octave couplers will be termed the "primary" knee-swell and the device which under the action of the knee simultaneously opens both 20 swell-shutters will be termed the "secondary" or "double-forte" knee-swell.

The primary knee-swell consists of a pair 25 of rock-shafts b and b' , mounted in suitable bearings b^2 and b^3 , respectively, at the right-hand and left-hand ends of the base 1, and a connecting rod or link b^4 , which is provided 30 with a dependent knee-piece b^5 and is connected at its ends to depending crank portions or arms b^6 and b^7 of said rock-shafts b and b' , respectively. The rock-shaft b is provided 35 with offset portions b^8 , which engage the under and free edges of the treble mute-valves 9 and 11, and between said offset portions b^8 or at some other suitable point said rock-shaft b is provided with a third offset portion b^9 .

b^{10} indicates a transversely-extended rock shaft or rod which is suitably mounted in the framework of the device and is provided 40 at its inner end with a laterally-bent finger portion b^{11} , which underlies the free edge of the leaf 14 of the treble-octave coupler. At 45 its outer end the rock-shaft b^{10} is provided with an arm or extension b^{12} , which, as shown, is bent to form an eye b^{13} and is then projected on downward and forward to form a lifting-finger b^{14} .

b^{15} indicates a plunger which is mounted 50 for vertical movement in suitable keepers or guides, as shown, in the form of eyes b^{16} , secured to the right-hand end plate 2. The lower end of this plunger b^{15} rests upon the offset projection b^9 of the rock-shaft b , and the lifting projection b^{14} of the rock-shaft b^{10} rests upon the upper end of said plunger b^{15} .

The rock-shaft b' at the left-hand side of 55 the organ, as viewed in Fig. 1, and at the right-hand side, as viewed in Fig. 3, is provided with a pair of offset or projecting portions b^{17} , which engage one under each of the mute-valves 10 and 12 and when raised open 60 said valves. At its intermediate portion this rock-shaft b' is provided with an inwardly-projecting arm b^{18} .

b^{19} indicates a transversely-extended rock shaft or rod similar to the rock-shaft b^{10} and 65 provided with a laterally-turned finger b^{20} , which underlies the free edge of the leaf 15 of the bass-octave coupler. This rock-shaft

b^{19} is suitably mounted in the framework of the organ and is provided at its outer end with an arm b^{21} , which is bent to form an eye 70 b^{22} and is then turned downward and rearward to form a hook b^{23} . A flexible connection b^{24} , having looped ends, connects the free end of the arm b^{18} of the rock-shaft b' with the said hook b^{23} . 75

It is of course evident after tracing the connections of the primary knee-swell that when the connecting-rod b^4 is forced toward the left, with respect to Fig. 1, by pressing the knee against the depending projection b^5 or, 80 preferably, against an ordinary-hinged knee-piece (not shown) having contact with said projection b^5 the rock-shafts b and b' will be simultaneously rocked and all four of the mute-valves will thereby be simultaneously 85 opened and both of the octave-couplers will be simultaneously operated.

The secondary or double forte knee-swell comprises in its preferred form a longitudinally-extended rock-shaft c , mounted in suitable bearings c^1 on the right-hand end of the support 1, and a transversely-movably knee-rod c^2 , mounted in a bearing c^3 on said base 1, and provided with an upturned arm c^4 , that is pivoted to an arm or crank portion c^5 95 of said rock-shaft c . The downturned end c^6 of the knee-rod c^2 is adapted to be directly engaged by the right knee of the operator, but would preferably be directly engaged by an ordinary hinged knee-piece. (Not shown.) 100 Near its forward end the rock-shaft c is provided with an inwardly-extended arm or lifting projection c^7 , that underlies the free edge of the forward forte-valve or swell-shutter 6, and at its rear end said rock-shaft is provided with a lifting-arm c^8 , that underlies the free edge of the rear forte-valve or swell-shutter 5. For an important purpose, to be hereinafter noted, the lifting-arm c^8 is provided 105 with a projection or eye c^9 . It is of course obvious that when the knee-rod c^2 is forced toward the right, with reference to Fig. 1, the rock-shaft c will be rocked and both forte-valves 5 and 6 will thereby be simultaneously opened. 110

The eight stops shown have marked on their heads or forward ends, successively, from left toward the right, with reference to Fig. 1, the following abbreviations, to wit: "Octv.," indicating octave; "Diap.," indicating diapason; 115 "Prin.," indicating principal; "1st f.," first forte; "2nd f.," indicating second forte; "ff.," indicating double forte; "Piano" and "Melo.," indicating melodia. These stops will be hereinafter referred to by the use of their abbreviations. The crank-pin a^3 of the "Diap." stop is connected by a cord or flexible connection f with a projecting arm f' of a rock-shaft f^2 , mounted in suitable bearings f^3 and 120 provided with an offset or projected arm f^4 , which underlies the rear bass-reed mute-valve 12. Hence, when this stop is given approximately ninety degrees of movement or 125 any other predetermined amount this rear

member of the bass-reed mute-valves will be opened wide. The crank-pin a^2 of the "Prin." stop is connected by a cord or flexible connection g to an arm g' of a short transverse rock-shaft g^2 , mounted in suitable bearings g^3 , and provided at its outer end with an arm g^4 , having the hooked end. The hooked end of this arm g^4 is connected by a coupling clip or piece g^5 and cord or flexible connection g^6 to an arm g^7 of a rock-shaft g^8 , that is mounted in one of the bearings f^3 and in a bearing g^9 , and is provided at its intermediate portion with a projecting arm or offset portion g^{10} , which underlies the free edge of the forward bass-reed mute-valve 10. Hence when this stop is moved by rotating the same the forward bass-reed mute-valve 10 will be opened. The crank-pin a^2 of the "1st f." stop is connected by a flexible connection or cord h to the free edge of the rear forte-valve or swell-shutter 5, the same as shown being directly connected to an eye h' on said valve or shutter. Obviously the rotary movement of this stop will open the rear forte-valve or swell-shutter. The crank-pin a^2 of the "2nd f." stop is connected by a cord or flexible connection k to an arm k' of a rock-shaft k^2 , which extends from front to rear of the framework shown and is mounted in suitable bearings k^3 . At its forward end this shaft k^2 is provided with another crank or arm k^4 , which is connected by a cord or flexible connection k^5 to the free edge of the forward or front swell-shutter 6, the connection to said shutter, as shown, being made directly to an eye k' on said shutter. It of course follows from these connections just described that when this latter-noted stop is turned the forward or front swell-shutters 6 will be opened. The double forte stop is provided with a connection whereby its movement will simultaneously open both of the forte-valves or swell-shutters. In the specific arrangement shown this result is accomplished by connecting the crank-pin a^2 of the "ff." stop by means of a cord or flexible connection n to an arm n' of a short transverse rock-shaft n^2 , mounted in suitable bearings n^3 n^4 and provided at its outer end with an arm n^5 , having a hooked end that is in turn connected to the projection c^9 on the arm c^8 of the rock-shaft c by means of a cord or flexible connection n^6 and a clip n^7 . Of course with these connections the partial rotation of the "ff." stop will rock the rock-shaft c and simultaneously open both of the swell-shutters. The crank-pin a^2 of the "Piano" stop is connected by a cord or flexible connection p to an arm p' of a short rock-shaft p^2 , suitably mounted in the bearing n^8 and another bearing p^9 , and provided at its outer end with an arm p^4 , having a hooked free end. This free end of the arm p^4 is connected by a cord or flexible connection p^5 and clip p^6 to the free end of a pin or projection p^7 , which rises from the forward member 9 of the treble-reed mute-valves. These connections are such

that when the "Piano" stop is turned the said valve 9 will be opened. The crank-pin a^2 of the "Melo." stop is connected by a cord or flexible connection r to an arm r' of another short rock-shaft r^2 , which is suitably mounted in the bearing n^3 and in a bearing r^3 , and is provided at its outer end with an arm r^4 , the free end of which is hooked. In like manner to the arm p^4 the free end of this arm r^4 is connected to the free end of a pin or projection r^5 on the free edge of the rear member 11 of the treble-reed mute-valves by means of a cord r^6 and clip r^7 . Again, it is evident that the partial rotation of this latter noted stop will open said mute-valve 11.

The "Octv." stop has clamped to its intermediate portion a divided spring-arm t , the prongs of which, as shown, tightly clamp a leather block t' under the action of a screw t^2 , and, as shown, the said arm t is prevented from slipping on said stop by a key t^3 . The block t' works on the crank portion t^4 of a transversely-extended rock-shaft t^5 , suitably mounted in one end plate 2 and in a bearing t^6 , and provided at its outer end with an arm t^7 , that is hooked at its free end. This free end of the arm t^7 is connected by a cord or flexible connection t^8 and clip t^9 to the previously-noted eye b^{22} of the arm b^{21} of the shaft b^{20} , which operates the bass-octave coupler, as previously noted. Now it is evident that when this last-described stop is partially rotated it will through the connections just noted open up or put in operation the bass coupler. Attention is here called to the fact that the movement of this "Octv." stop will not actuate the rock-shaft b' of the primary knee-swell, and, on the other hand, that the operation of the primary knee-swell will not act upon the rock-shaft b' and arm t' . When this arm t' is turned into its operative position, it will depend straight downward and will engage the crank portion t^4 of the shaft t^5 approximately at a perpendicular thereto, and it will thus be frictionally held where set. Another key, such as any of those above described, may be provided with connections to a cord v , or this cord v may be connected to one of the keys and connections already shown. In either case the treble-octave coupler could be operated by a stop.

In connection with one or any number of the stops I provide a device or devices for frictionally holding said stop or stops at any intermediate point or points between their extreme movements. The purpose of such construction is to enable the stop to be set so that it will have variable actions on the valves or mechanisms which it controls. As shown in Figs. 4 and 6, this friction device is applied to the "Melo." stop, and it consists of a split spring-clamp w encircling said stop, with one end secured to the stop-frame 3 by a screw w' and having its other end drawn against the body of said stop by another screw w^2 . By means of this screw w^2 the

tension of the clamp w on the stop may be properly set. It may of course be applied to any of the other stops.

In Figs. 7 and 8 the exact relation of the clip t^6 to the hook end of the arm t^7 is illustrated, and by reference to these figures it will be noted that said clip t^6 has a perforation t^{10} , through which the hooked end of said arm t^7 is adapted to be passed, and is also provided with a notch t^{11} , adapted to embrace the body of said arm while the clip is being placed in working position. The same specific construction is shown as applied to the other clips; but it will not be necessary to further note the same.

In Fig. 9 one of the detachable looped ends of the connections to the crank-pins a^2 of the stops is illustrated. This may be assumed to be the upper end of the cord or connection h , and it may be noted that the loop is formed by connecting the downturned end of said cord to the body portion thereof by means of a clenched metallic band h^2 .

It is obvious that the several specifically-different connections between the various stops and the valves or other devices which they operate may be substituted or interchanged in constructing or rearranging organs. For example, the so-called "spring-arm" used in connection with the bass-octave coupler might be applied to any other of the stops, or, vice versa, any of the other forms of connection might be applied to this particular stop. This spring-arm construction has the advantage that it may be very readily applied to the sliding stops of organs now in use to convert the same into an organ having rotary stops. However, the crank attachments may also be quite easily applied in the same way and for the same purpose. As previously indicated, the friction device for holding the stops in intermediate set positions may also be applied to any or all of the stops. Furthermore, as previously indicated, any desired number of additional stops provided with any of the connections above described may be provided. The spring-arm t being split or divided adapts it for application to the stops of an ordinary organ, thereby making it possible to very readily convert the sliding stops into rotary stops.

It will of course be understood that alterations in the details of construction above set

forth may be made within the scope of my invention. For example, the rotary stops 55 might be given complete rotations instead of partial rotations, as illustrated. Again, the construction herein described while having a particular relation to reed-organ construction may in many cases be applied to pipe-60 organ constructions.

Having now described my invention, what I claim, and desire to secure by Letters Patent of the United States, is as follows:

1. In an organ, the combination with a knee-swell involving a rock-shaft having a projection connected to one of the sound-actuating devices, by a cord or flexible connection, of a rotary stop operating on said sound-controlling device through a flexible connection, 65 whereby the actions of said stop and knee-swell do not interfere one with the other.

2. In an organ, the combination with a rotary stop connected to the sound-controlling mechanism actuated thereby, of a friction-brake applied to said stop for frictionally holding the same in various intermediate positions, which brake consists of a split spring-clamp, means for securing said clamp against rotation, and means for variably drawing said 80 clamp onto said stop to put the same under slipping friction, to move in either direction, substantially as described.

3. In an organ, the combination with one of the stops and sound-controlling mechanism actuated thereby, of connections between the same involving the hooked arm t^7 , the flexible connection and the clip t^6 secured to said flexible connection, and having the perforation t^{10} and notch t^{11} engageable with said 90 hooked end, substantially as described.

4. In a reed-organ, a finger-operated stop having suitable connections to the sound-controlling mechanism operated thereby, in combination with a friction-brake applied to said stop, which friction-brake is adapted to be set for a predetermined tension and when set to frictionally hold said stop against movement, in either direction, substantially as described.

In testimony whereof I affix my signature in presence of two witnesses.

JAMES WYVELL.

Witnesses:
